UNITED STATES PATENT OFFICE

DIBRELL P. HYNES, OF CHICAGO, ILLINOIS, ASSIGNOR TO CHICAGO FORGING & MANUFACTURING COMPANY, OF CHICAGO, ILLINOIS, A CORPORATION OF ILLINOIS

WINDOW CURTAIN SUPPORT

Application filed October 8, 1928. Serial No. 310,982.

My invention relates to an improvement in window attachments and more particularly to a device adapted to raise the lower end or intermediate portion of a window curtain above the opening provided by raising the lower window sash. An object is the provision of an improved construction of this character which shall be highly efficient in use and economical in manufacture. An other object is the provision of such means which shall be adjustable. Other objects will appear from time to time in the course of the specification and claims.

I illustrate my invention more or less diagrammatically in the accompanying drawings, wherein—

Figure 1 is a front elevation of a window equipped with my device;

Figure 2 is a section on the line 2—2 of Figure 1;

Figure 3 is a section on the line 3—3 of Figure 1;

Figure 4 is a section on the line 4—4 of Figure 3;

Figure 5 is a section on the line 5—5 of Figure 1;

Figure 6 is a front elevation of a window equipped with a variant form of my device;

Figure 7 is a section on the line 7—7 of Figure 6;

Figure 8 is a section on the line 8—8 of Figure 6;

Figure 9 is a detail front view;

Figure 10 is a detail plan view;

Figure 11 is a transverse vertical section; Figures 12, 13, 14 and 15 are details; and Figure 16 is a transverse vertical section through another portion of my device.

Like parts are indicated by like symbols throughout the specification and drawings.

A generally indicates a window frame, A¹ the upper sash and A² the lower sash.

B generally indicates a base or body member positioned in the lower sash for example by the screws B¹. It is herein illustrated as positioned at the upper corners of the sash. It will be realized that a similar result may be obtained by positioning it on the lower corners of the movable sash. The base or body member B is provided with opposed

parallel outwardly projecting flanges B² between which is pivoted the arm B³ into which telescopes the rod B⁴. B⁵ is a bolt on which the member B³ is pivoted, B⁶ being a lock nut whereby the member B³ may be set or locked in any desired angular adjustment. Whereas I have described a practical supporting and locking arrangement it will be realized that I do not wish to be limited specifically thereto. The rod B⁴ is herein shown as snugly fitting in the member B³. It will be realized that any suitable means may be employed for locking it in any given position for example the screw B⁷.

C indicates a transverse curtain engaging rod herein shown as passing through an eye B⁸ at the end of the rod B⁴. The rod may be provided with a shoulder or reduced portion as at C¹, screwthreaded as at C² to receive the lock nut C³.

D indicates the curtain suspended for example on the upper curtain rod D¹ upon any suitable brackets or supports D² at the top of the widow. The curtain is secured to the rod C, intermediate its length, as by the double portion D³.

Referring to Figure 2 and particularly to the dotted line showing therein it will be observed that the members B³ B⁴ may be so adjusted as to position the rod C somewhat out of line with the upper rod D¹. The purpose of this is to permit the curtain to loop easily in response to upward movement of the sash.

In order to adjust the length of the curtain and to adjust the height of the rod C to curtains of different length and to allow for shrinkage I provide the pivotal adjustment of the entire curtain supporting member formed by the members B³ B⁴. In order properly to align the rods C with the rod D¹ or in order to position it out of alignment with the upper rod, I provide the axial adjustment with the member B⁴ in relation to B³.

This also permits the position of the lower edge of the curtain in relation to the window frame or sill to be adjusted, it being sometimes desirable to have the curtain hang above the sill and under some conditions to

have it hang beyond the sill and below it, as shown in Figure 2.

Referring to the form of Figures 6 and following I employ the adjustable supporting members for the top and the intermediate portion of the curtain. In the form herein shown I illustrate the curtain rod upon which the top of the curtain is supported and an intermediate curtain rod to 10 which the curtain is secured intermediate top and bottom. Both these curtain rods are shown as mounted on adjustable supports or brackets, these supports being adjustable both horizontally and vertically.

15 Referring to Figures 8 to 15 inclusive, which relate to the support shown for the lower rod in Figures 6 and 7 I employ a base member E which is shown as secured to the lower sash A² frame by the flange E¹ and the screws E². This base member is provided with an aperture E³, which may be screw threaded and an adjustment aperture E⁴, herein provided with a plurality of recesses E⁵. Mounted upon the member E is 20 the supporting bracket G which is longitudinally slotted as at G¹ and is provided with a notch G² adapted to receive the reduced portion G³ of the curtain rod G⁴.

G⁵ is any suitable locking member for the 30 notch G², herein shown as pivoted as at G⁶ provided with the locking stud G⁷.

H generally indicates the locking screw with the thumb piece H¹ and the screw-threaded portion H² adapted to penetrate 35 the screwthreaded aperture E³. H³ generally indicates a clamp member with the off-set portion H⁴ adapted to penetrate the slot G¹ of the bracket G and the pin H⁵ adapted to seat in one of the recesses E⁵ of the aperture E⁴.

40 It will be understood that when the member H³ is seated against the bracket G with the off-set portion H⁴ in the slot of the bracket and the pin H⁵ in one of the apertures E⁵, tightening up of the thumb screw H preventing movement of the parts away from the base portion E, locks the entire assembly fixed in the position in which it is set. Adjustment is effected by loosening or 45 removing the thumb nut sufficiently to permit the member H³ to be rotated to position the pin H⁵ in a different notch. Also, when the thumb nut is loosened it is possible to adjust the bracket longitudinally owing to 50 its longitudinal slot G¹.

55 Figure 16 illustrates the upper curtain supporting member in which I employ in place of the base member E a more extended base or bracket portion J with its flange J¹ adapted to be secured by screws E² to the upper movable sash A¹. The base portion J is slotted as at J² to receive the trunnion K¹ illustrated in dotted lines in Figure 16, of one end of any suitable window shade K.

60 It will be realized that whereas I have de-

scribed and shown a practical and operative device, nevertheless many changes might be made in size, shape, number and disposition of parts without departing from the spirit of my invention. I therefore wish my description and drawings to be taken as in a broad sense illustrative and diagrammatic rather than as limiting me to my specific showing.

65 The use and operation of my invention are as follows:

In the present accepted practice of employing, with a liftable sash, a curtain suspended only at the top, when the sash is lifted the curtain remains in its original position and may be blown out of the window and soiled, or may be effected by rain or dust blowing in through the window. I 70 find it desirable to provide means for lifting the bottom of the curtain with the sash in such fashion that when the sash is lifted no substantial portion of the curtain depends beneath the bottom of the sash. This 75 prevents the curtain from being blown about and also protects it from rain and, to a very 80 substantial extent, from external dust.

85 In practice there is a considerable variation in length of curtain or even of the same curtain, owing for example to shrinkage in washing. I therefore find it desirable 90 to provide adjustable supports for said curtain either at the top of the curtain or intermediate the ends of the curtain, or at 95 both points. I have illustrated in the present application a plurality of forms of such 100 supports and wish to emphasize the importance both of a vertical adjustment of such supports and of a horizontal adjustment toward or away from the vertical plane of 105 the sash.

110 Referring to the form of Figures 1 to 5 inclusive I have illustrated a base member secured to the sash or, if desired, to the top of the frame, which base member has pivoted to it a bracket B³ rotatable about a horizontal axis. The rotation of this bracket about its horizontal axis provides the vertical adjustment.

115 The horizontal adjustment, or adjustment toward or away from the sash, is provided by associating with the member B³ the telescopic member B⁴, whereby the bracket assembly may be shortened or lengthened at will. It will be realized that whereas in 120 Figures 1 and 2 I have shown this support as employed only upon the sash it may, if desired, be employed also at the top of the curtain.

125 Referring to Figures 6 and following I illustrate a variant form of my device in which a single movable bracket member G may be adjusted both vertically and horizontally. The vertical adjustment is effected by rotating it about a pivot point on the base member and the horizontal ad-

justment is effected by moving it horizontally in relation to such pivot point, the bracket being slotted longitudinally to permit such movement.

5 It will be noted in Figure 7 that the upper curtain supporting bracket J which is also adapted to carry any suitable window shade K is secured to the upper movable sash, thus if the upper sash is lowered, the curtain and window shade are both protected from being blown about and from external dust and rain.

10 I am aware of the fact that it is old to pivot a curtain raising element upon a sash for movement in response to movement of the sash. It is one object of my invention to provide a device in which the curtain supporting or engaging element is normally fixed on the sash and moves unitarily with the sash. I wish it to be understood, when in the claims I specify means for adjusting the curtain raising element either laterally or vertically, that I wish the claims to be interpreted as calling for an adjustment of 15 such element in relation to the sash, such adjustment being independent of any rotation or movement of the curtain engaging element in relation to the sash.

I claim:

20 1. The combination with a movable window sash of a curtain raising element adapted to engage said curtain and mounted upon said sash, and means for adjusting said curtain raising element laterally toward and away from said sash.

25 2. The combination with a movable window sash of a curtain raising element adapted to engage said curtain and mounted upon said sash, said curtain raising element being vertically adjustable in relation to said sash.

30 3. The combination with a movable window sash of a curtain raising element adapted to engage said curtain and mounted upon said sash, and means for adjusting said curtain raising element laterally toward and away from said sash, and for adjusting said curtain raising element vertically in relation to said sash.

35 4. The combination with a movable window sash of a curtain raising element adapted to engage said curtain and mounted upon said sash, and supports for said curtain raising element extending outwardly away from said sash and adjustable as to length.

40 5. The combination with a movable window sash of a curtain raising element adapted to engage said curtain and mounted upon said sash, and supports for said curtain raising element extending outwardly away from said sash, said supports being vertically adjustable in relation to said sash.

45 6. The combination with a movable window sash of a curtain raising element adapted to engage said curtain and mounted upon said sash, and supports for said curtain rais-

ing element extending outwardly away from said sash, the outer ends of said supports being adjustable vertically in relation to said sash.

70 7. The combination with a movable window sash of a curtain raising element adapted to engage said curtain and mounted upon said sash, and supports for said curtain raising element extending outwardly away from said sash, said supports being pivotally adjustable in relation to said sash.

75 8. The combination with a movable window sash of a curtain raising element adapted to engage said curtain and mounted upon said sash, and supports for said curtain raising element extending outwardly away from said sash, said supports being pivotally adjustable in relation to said sash, and being adjustable as to length.

80 9. The combination with a movable window sash of a curtain raising element adapted to engage said curtain and mounted upon said sash, said element including a bracket member adapted for both horizontal and vertical adjustment in relation to said sash.

85 10. The combination with a movable window sash of a curtain raising element adapted to engage said curtain and mounted upon said sash and supports for said curtain raising element including a base element on said sash, a bracket mounted upon said base element, means for vertically angularly adjusting said bracket in relation to said base element, and means for adjusting said bracket in a generally horizontal plane inwardly and outwardly in relation to said base and the sash.

90 11. The combination with a window frame and a lower and an upper movable sash mounted therein, of an adjustable support adapted to receive the top of the curtain, mounted upon the upper sash, and an adjustable support adapted to engage the intermediate portion of the curtain, mounted on the lower sash.

95 12. The combination with a window frame and a lower and an upper movable sash mounted therein, of a vertically adjustable support adapted to receive the top of the curtain, mounted upon the upper sash, and a vertically adjustable support adapted to engage the intermediate portion of the curtain, mounted on the lower sash.

100 13. The combination with a window frame and a lower and an upper movable sash mounted therein, of a horizontally adjustable support adapted to receive the top of the curtain, mounted upon the upper sash, and a horizontally adjustable support adapted to engage the intermediate portion of the curtain, mounted on the lower sash.

105 14. The combination with a window frame and a lower and an upper movable sash mounted therein, of a horizontally and vertically adjustable support adapted to re-

ceive the top of the curtain, mounted upon the upper sash, and a horizontally and vertically adjustable support adapted to engage the intermediate portion of the curtain, mounted on the lower sash.

15. The combination with a window frame and a lower and an upper movable sash mounted therein, of a fixed window shade supporting means, mounted upon the upper sash, and an adjustable curtain support associated therewith, adapted to support the top of a curtain, and an adjustable support for the intermediate portion of a curtain, mounted on the lower sash.

16. In a curtain raising mechanism including a curtain raising element and supports for mounting the same on a movable window sash, said supports including a base member and a slotted bracket adjustably mounted thereon, the combination with the support and bracket, of a clamp member having an offset portion engaging the slot in the bracket and an additional offset portion non-rotatably engaging the base whereby the bracket is held in an adjustable position on the support.

17. In a curtain raising mechanism including a curtain raising element and supports for mounting the same on a movable window sash, said supports including a base member and a slotted bracket adjustably mounted thereon, the combination with the support and bracket, of a clamp member having an offset portion engaging the slot in the bracket and an additional offset portion penetrating the base, said base being apertured to receive said additional offset.

18. In a curtain raising mechanism including a curtain raising element and supports for mounting the same on a movable window sash, said supports including a base member and a slotted bracket adjustably mounted thereon, the combination with the support and bracket, of a clamp member having an offset portion engaging the slot in the bracket and an additional offset portion penetrating the base, said base being provided with a plurality of apertures to be engaged by said offset portion in various adjusted positions.

Signed at Chicago, county of Cook and State of Illinois, this 15th day of September, 1928.

DIBRELL P. HYNES.
